[57] CLAIM

The ornamental design for a combined fan and cover therefor, as shown and described.

DESCRIPTION

FIG. 1 is a front elevation view of a combined fan and cover therefor, showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a perspective view thereof; and,

FIG. 7 is a perspective view of the fan shown separately with the cover removed for clarity of illustration.

The bottom of the fan is plain and unornamented and has been omitted.
